CONTAINER CLOSURE

Karl M. Langenstein, New Orleans, La.

Application February 6, 1941, Serial No. 377,722

1 Claim. (Cl. 65—31)

The present invention relates to new and useful improvements in closures for containers particularly for dispensing syrups, salad oils and dressings, etc., and has for its primary object to provide, in a manner as hereinafter set forth, a device of this character embodying a novel construction and arrangement of pouring spout which, when not in use, is enclosed in and concealed and protected by the container.

Another very important object of the invention is to provide a container closure of the aforementioned character wherein the pouring spout is automatically brought into position for use when the cover or lid is opened.

Still another very important object of the invention is to provide a closure of the character described which is adapted to seal the container and which, further, includes means for retaining the cover or lid in either open or closed position.

Other objects of the invention are to provide a container closure of the character set forth which will be comparatively simple in construction, strong, durable, highly efficient and reliable in use, compact, attractive in appearance and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in side elevation of a closure constructed in accordance with the present invention, showing the device mounted on a container.

Figure 2 is a top plan view thereof.

Figure 3 is a view principally in vertical section through the closure and the container, showing the pivoted cover open with the pouring spout in operative position.

Figure 4 is a fragmentary view in horizontal section, taken substantially on the line 4—4 of Figure 3.

Referring now to the drawings in detail, it will be seen that the embodiment of the invention which has been illustrated comprises a ring 1 of suitable material which is adapted to be threaded on the neck 2 of a conventional container 3. On the upper end of the ring 1 is an internal flange 4. Mounted in the upper portion of the ring 1 is a rubber gasket or annulus 5 which is secured in position on the top of the container neck 2 by the flange 4.

Formed integrally with the ring 1 and extending

outwardly and downwardly therefrom is a handle 6. Projecting from the upper portion of the handle 6 is a grooved lug 7. Below the lug 7 the handle 6 has formed therein a groove or channel 8 the purpose of which will be presently set forth.

Pivotedly mounted at 9 on the upper portion of the handle 6 is an arm 10 of substantially channel shaped cross section. Formed integrally with the pivoted end of the arm 10 is a cover 11 in the form of a disk. The lower side of the cover 11 is provided with an annular bead or rib 12 which is adapted to seat on the gasket 5 for sealing the container 3 when said cover 11 is in closed position. It will be observed that the rubber gasket 5 extends inwardly from the flange 4 in a manner to receive the bead 12.

Mounted longitudinally in the arm 10 is a coil spring 13. One end of the coil spring 13 is engaged in the groove of the lug 7 for retention thereby. The other end of the coil spring 13 is engaged with and retained by a suitable lug 14 on the free or outer end of the arm 10.

Mounted on the lower side of the cover 11 is a pouring spout 15 of arcuate cross section. The pouring spout 15 includes a pair of integral arms 16 which are rigidly secured at 17 to the lower side of the cover 11. The lower end of the pouring spout 15 is formed to provide a lip or shoulder 18 which is engageable beneath the gasket 5 when said spout is in pouring position.

It is thought that the operation of the device will be readily apparent from a consideration of the foregoing. With the cover 11 in closed position the pouring spout 15 depends from said cover into the container 3. The coil spring 13 presses the cover 11 downwardly thereby engaging the bead 12 with the rubber gasket 5 in a manner to seal the container 3. When it is desired to dispense the contents of the container 3 the cover 11 is swung upwardly to open position through the medium of the arm 10. This may be conveniently accomplished with the thumb of the hand which grips the handle 6.

When the cover 11 is in open position the lip or shoulder 18 of the spout 15 is engaged beneath the sealing gasket 5 in a manner to prevent the flow of the container contents therebetween. The contents of the container may now be dispensed in an obvious manner. The groove or channel 8 in the upper portion of the handle 6 accommodates the coil spring 13 when the cover 11 is in open position. The spring 13 also urges the cover 11 upwardly when in open position in a manner to press the lower portion of the spout

15, with the lip or flange 18, against the gasket 5. The construction and arrangement is such that the coil spring 13 swings past dead center when the cover 11 is opened or closed. Thus, the spring 13 constitutes means for securing the cover in either open or closed position.

It is believed that the many advantages of a container closure constructed in accordance with the present invention will be readily understood and although a preferred embodiment of the device is as illustrated and described, it is to be understood that changes in the details of construction and in the combination and arrangement of

parts may be resorted to which will fall within the scope of the invention as claimed.

What is claimed is:

5 A container closure of the class described comprising a ring for mounting on a container, a sealing gasket mounted in said ring, a cover pivotally mounted on the ring, a bead on said cover engageable with the sealing gasket, a pouring spout on the cover movable thereby to operative position and engageable with the sealing gasket when in operative position, and means for releasably securing the cover in open or closed position.

KARL M. LANGENSTEIN.
